Primary Examiner — Vy N Koenig*Assistant Examiner* — Elizabeth Anne Glassberg(74) *Attorney, Agent, or Firm* — Justin Lampel(57) **CLAIM**

The ornamental design for a cat house, as shown and described.

DESCRIPTION

FIG. 1 is a first perspective view of a cat house showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a perspective view of the cat house of FIG. 1 shown in a second configuration with the top cover rolled up to show the top opening; and,

FIG. 10 is a perspective view of the cat house of FIG. 1 shown in a third configuration with the flaps up on all the side openings.

The broken lines in the drawings depict portions of the cat house that form no part of the claimed design.

1 Claim, 10 Drawing Sheets(56)
